UNITED STATES PATENT OFFICE

LOUIS FOLOFSON KIRSCH, OF CLEVELAND, OHIO

DESIGN FOR A RADIOCABINET

Application filed April 4, 1930. Serial No. 35,157. Term of patent 14 years.

To all whom it may concern:

Be it known that I, LOUIS F. KIRSCH, a citizen of the United States, residing at Cleveland, in the county of Cuyahoga and State of Ohio, have invented a new, original, and ornamental Design for Radiocabinet, of which the following is a specification, reference being had to the accompanying drawing, forming part thereof.

Figure 1 is a front elevation of my radio cabinet.

Fig. 2 is an end elevation of the radio cabinet, showing my new design.

I claim:

The ornamental design for a radio cabinet as shown.

LOUIS FOLOFSON KIRSCH.
